DESIGN FOR A FOOT PLATE FOR ROLLER SKATES

Roland H. Goetsch, Milwaukee, Wis., assignor to
Globe-Union Inc., Milwaukee, Wis., a corporation
of Delaware

Application November 1, 1939, Serial No. 87,985

Term of patent 7 years

To all whom it may concern:

Be it known, that I, Roland H. Goetsch, a citizen of the United States, residing at Milwaukee, in the county of Milwaukee and State of Wisconsin, have invented a new, original, and ornamental Design for a Foot Plate for Roller Skates, of which the following is a specification, reference being had to the accompanying drawing, forming a part thereof, and in which:

Fig. 1 is a plan view of a foot plate for roller skates, showing my new design;

Fig. 2 is a side elevational view thereof;
Fig. 3 is a sectional view taken on line 3—3 of
Figure 1; and

Fig. 4 is a sectional view taken on the line 4—4 of Fig. 1.

I claim:

The ornamental design for a foot plate for roller skates, as shown.

ROLAND H. GOETSCH.
